CLAIM

The ornamental design for a desk task lamp, as shown and described.

DESCRIPTION

FIG. 1 is a top perspective view of a desk task lamp showing my new design;

FIG. 2 is a left side elevation view thereof, the right side being a mirror image thereof;

FIG. 3 is a back elevation view thereof; and,

FIG. 4 is a front elevation view thereof.

The subject matter shown in broken lines forms no part of the claimed design. The bottom view forms no part of the claimed design.
